UNITED STATES PATENT OFFICE.

CLAUDE C. NUCKOLS, OF MENANDS, NEW YORK, ASSIGNOR TO CONSOLIDATED CAR-HEATING COMPANY, OF ALBANY, NEW YORK, A CORPORATION OF WEST VIRGINIA.

STEAM-HEATING SYSTEM.

1,247,711.

Specification of Letters Patent. Patented Nov. 27, 1917.

Application filed August 18, 1915. Serial No. 46,168.

To all whom it may concern:

Be it known that I, CLAUDE C. NUCKOLS, a citizen of the United States, and a resident of Menands, Albany county, and State of New York, have invented certain new and useful Improvements in Steam-Heating Systems, of which the following is a description.

My invention relates to steam heating systems which, while they may be applied to the heating of any desired apartment, are more particularly applicable to the heating of railway cars. My invention may advantageously be applied to systems in which the inflow of steam is controlled, as, for instance, the atmospheric system.

The principal objects of my invention are to produce a steam heating system which shall be simple, effective, require the least amount of attention, and shall operate automatically to maintain an approximately constant temperature within the apartment to be heated, irrespective of the variation of external temperature and weather conditions.

In prior steam heating systems of the atmospheric type, it is the practice to connect the radiator in the apartment with a supply pipe (which carries steam at pressure higher than atmospheric) through an inlet valve, which inlet valve is controlled by means of a thermostatic element located outside the apartment to be heated and in the line of the radiator discharge, so that the thermostat is subjected both to the influence of external weather conditions and to that of the exhausted heating medium, the temperature of the latter being a function of the temperature condition of the apartment.

While this regulation obtains good results and is automatic to a degree, it is, nevertheless, not completely automatic, by reason of the fact that with such an arrangement the radiating pipes are maintained filled with steam at atmospheric pressure and, therefore, are maintained at a temperature of substantially 212 degrees.

Thus, while it is apparent that in such a system fresh steam is constantly supplied to make up for condensation which occurs through the tendency of the apartment to cool, nevertheless, the amount of heat which may be transmitted from the radiator to the air of the apartment is limited by the amount of air which can be moved over the

radiator coils, or, in other words, by the radiator surface. Thus, if a radiator intended to be maintained at 212 degrees be proportioned to properly meet the heat demand for a certain external temperature, it is possible, and it frequently occurs in practice, that in very cold weather such a radiator is insufficient, by reason of its limited surface, to maintain the temperature of the apartment. On the other hand, when the weather is mild, the radiator pipes being full of steam at 212 degrees, the car may be over-heated.

My invention aims to obviate these defects, while preserving the desirable features of the prior construction, and, to this end, I have arranged my apparatus so that the control of the inflow of the heating medium may be taken away from the externally exposed thermostatic element and given over to an element responsive to the apartment temperature. At the same time, however, I do not deprive the apparatus of the valuable mode of operation it has by reason of the externally exposed thermostat controlling the intake valve, and of the peculiar and advantageous compounding effect produced upon such thermostat by reason of the fact that it is also exposed to the radiator discharge.

In the drawing accompanying this specification, I have shown a portion of a railway passenger car to which my invention is applied.

Beneath the floor 1 of the car is the train line 2, which takes steam from the locomotive and extends the length of the train. A branch 3 from the train line enters an inlet valve-casing 4, containing a valve 5, thus permitting steam to flow from the train line 2 into a riser 6, communicating with the radiator 7. The radiator discharges through a pipe 8, into a casing 9, containing a thermostatic element 10, here shown to be in the form of a flat metal box containing an expandible fluid, such as alcohol. The casing 9 is provided with apertures 11, through which the exhaust of the radiator escapes, and through which air may reach the thermostatic element 10. Resting upon thermostatic element 10 is a rod 12 which, by means of a bell crank 13, is adapted to actuate valve 5. Thus when the discharge of the radiator falling upon the diaphragm or thermostatic element 10, and the effect of

the external atmosphere and windage have reduced the temperature of diaphragm 10 until the fluid contained therein liquefies, the valve 5 is opened, thus admitting more 5 steam to radiator 7, which, when it reaches the exhaust and is discharged upon diaphragm 10, expands the diaphragm to close the intake valve 5, thus keeping the pipes of the radiator filled with atmospheric steam.

10 Connected to rod 12, in any suitable manner, is a thermostatic element 14, here shown in the form of a sealed casing, although any other suitable form of thermostat may be used, which thermostatic element is located 15 within the car, or other apartment to be heated, and is, therefore subject to temperature variations of the air of the apartment. The form of connection between the thermostat 14 and the valve rod may be that shown 20 in the drawing, comprising a cable 15, connected by means of a spring 16, to rod 12, and by means of a bell crank or similar mechanism 17, to the thermostatic element 14. The spring 16 is preferably adjusted 25 by means of a thread 18 upon rod 12 to a tension sufficient to hold the valve 5 closed against the train line pressure when diaphragm 14 is expanded.

30 The operation of my improved apparatus is as follows:

The parts as shown in the drawing are in the position that they would assume were the radiator pipes full of steam and the diaphragm 10 expanded, steam being shut off. 35 When the radiator pipes cool and the diaphragm 10 is also cooled, by reason of the outside temperature and windage, the diaphragm 10 will contract, thus admitting more steam through valve 5.

40 Let us assume that the day is a mild one and that the surface of the radiator 7 is such that if it is kept entirely filled with steam at substantially 212 degrees the car will be over-heated. The thermostatic element 14 and its connections being properly 45 adjusted, say to operate at a temperature of 70 degrees, when the car reaches that temperature the thermostatic element 14 will be expanded, thus drawing upon the cable 15, and through bell crank 13 closing valve 5. Thermostatic element 14 thus takes control 50 of the inlet valve, the thermostatic element 10 being at that time contracted and ineffective to close the valve. The effect of the 55 operation of thermostat 14 will be to allow only sufficient steam to enter the radiator 7 to partially fill the radiator, the remainder of the radiator being filled with air entering through the open exhaust and a trickle 60 of water of condensation. The effective radiating surface has thus been diminished to below the normal radiating surface of the radiator, and the radiator may, therefore, be constructed sufficiently large to take care of 65 the lowest temperature encountered, with-

out at the same time making the radiator of too large a surface for mild weather. Heretofore attempts have been made to secure a regulation by cutting in and out sections of the radiator as they were needed or not. 70 But such an arrangement prevented an even distribution of the heat throughout the car and was unreliable because of the fact that train men were relied upon to open and close these cut-off valves. 75

It will be noted that the elastic member or spring 16 permits an extensive movement of the thermostatic element 14, without damage to any of the parts. The thermostat 14 may therefore be of a kind adapted to expand between relatively wide limits, and thus exert a strong pull against the inlet valve, without, however, incurring the danger of breaking the parts. 80

While I have only shown one form of my invention, it will be understood that many modifications may be made without departing from its spirit, and I therefore do not intend to be confined to the precise form shown and described. 85

What I claim as new and desire to secure by Letters Patent is:

1. An improvement in steam heating systems comprising a radiator, a valve controlling admission of heating fluid thereto, a trap connected with the outlet branch of the radiator, an operating rod within said trap operatively connected with said valve, a thermostat within said trap and engaging said rod, a second thermostat within the 100 space to be heated, and a movable member connected at one end with said rod and having its other end in operative relation with the second thermostat. 90

2. An improvement in steam heating systems comprising a radiator, a valve controlling admission of heating fluid thereto, a trap connected with the outlet branch of the radiator, an operating rod within said trap operatively connected with said valve, a thermostat within said trap and engaging said rod, a second thermostat within the space to be heated, a cable connected at one end with said rod and means operated by the second thermostat for exerting a pull 110 upon said cable. 105

3. An improvement in steam heating systems comprising a radiator, a valve controlling admission of heating fluid thereto, a trap connected with the outlet branch of the 120 radiator, an operating rod within said trap operatively connected with said valve, a thermostat within said trap and engaging said rod, a thermostat within the space to be heated, and a movable member having a 125 resilient connection at one end with said rod and having its other end in operative relation with the second thermostat. 130

4. An improvement in steam heating systems comprising a radiator, a valve control-

ling admission of heating fluid thereto, a trap connected with the outlet branch of the radiator, an operating rod within said trap operatively connected with said valve, a 5 thermostat within said trap and engaging said rod, a second thermostat within the space to be heated, a spring adjustably con- nected with said rod, and a movable member connected at one end with said spring and having its other end in operative relation with the second thermostat. 10

In witness whereof I have hereunto set my hand this 16th day of August, 1915.

CLAUDE C. NUCKOLS.
